UNITED STATES PATENT OFFICE.

LIBANUS M. TODD, OF ROCHESTER, NEW YORK.

DESIGN FOR A FRAME OR CASING FOR CHECK-PRINTERS.

SPECIFICATION forming part of Design No. 35,523, dated December 31, 1901.

Application filed November 18, 1901. Serial No. 82,784. Term of patent 14 years.

To all whom it may concern:

Be it known that I, LIBANUS M. TODD, of Rochester, in the county of Monroe and State of New York, have invented and produced a new and original Design for a Frame or Casing for Check-Printers, of which the following is a specification, reference being had to the accompanying drawings, forming a part thereof.

My design consists of the shape or configuration of a frame or casing for check-printers or stamping-machines adapted for embossing checks or other papers.

In the drawings, Figure 1 is a perspective view of a frame or casing embodying my design, and Fig. 2 is a side elevation thereof.

The design consists of an upper portion A, having the bulging forward side provided with the rounded face a, curving over the top of said portion, and which constitutes the

leading or material feature of the design. Below this portion is a base B, having the sides b extending outwardly slightly toward their lower edges.

C indicates a narrow slot or aperture extending between the base B and the bulging portion of the top A.

Having described my invention, what I desire to secure by Letters Patent is—

The design for a frame or casing for check-printers, substantially as shown and described.

In testimony whereof I have signed my name to this specification in the presence of two subscribing witnesses.

LIBANUS M. TODD.

Witnesses:

G. WILLARD RICH,
WALTER B. PAYNE.
